UNITED STATES PATENT OFFICE.

WILLIAM H. BOUTELLE, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,353,311.

Specification of Letters Patent. Patented Sept. 21, 1920.

Application filed July 29, 1919. Serial No. 314,077.

To all whom it may concern:

Be it known that I, WILLIAM H. BOUTELLE, a citizen of the United States, residing at Southbridge, in the county of Worcester and State of Massachusetts, have invented certain new and useful Improvements in Ophthalmic Mountings, of which the following is a specification.

This invention relates to improvements 10 in ophthalmic mountings and has particular reference to what is commonly known as a finger-piece mounting, or mounting retained on the face through the use of spring actuated clip arms.

15 The principal object of the present invention is the provision of novel and improved means for readily and securely fastening the arms and associated parts in position on the mounting.

20 A further object of the invention is the provision of securing means which may be instantly applied or detached, as desired.

Other objects and advantages of my improved construction should be readily apparent by reference to the following specification taken in connection with the accompanying drawings, and it will be understood that I may make any modifications in the specific details of construction shown and 25 described within the scope of the appended claims without departing from or exceeding the spirit of my invention.

Figure I represents a front view of a mounting embodying my improvements.

30 Fig. II represents an enlarged vertical sectional view of one side of such a mounting.

Fig. III represents a plan view of a side of the mounting.

40 Fig. IV represents an enlarged plan view of one form of locking member.

Fig. V represents a similar edge view thereof.

Fig. VI represents a detail view of a 45 slightly modified construction.

In the drawings the numeral 1 is employed to designate the bridge provided with a pivot seat 2, to which is preferably secured one end of the frame 3, adapted to 50 extend around the lens 4, having on its opposite end the end piece 5. Secured in the seat 2 is the threaded portion 6 of my pivot post 7 having engaged on its lower end the nut 8' of the end piece 5, by which the frame

is held in closed position around the lens 4. 55 The post 7 projects above the surface of the bridge 2 and is provided with the circumferential groove or channel 8', forming at its top the head 9, the head being flattened on two sides to be of substantially elliptical 60 form, as is clearly illustrated in connection with Fig. III.

Rotatably mounted upon the post 7 below the groove 8 is the fingerpiece lever 10, having the barrel portion 11 extending upward 65 around the post and encircled by the actuating spring 12. To satisfactorily retain the parts in position but permit of their ready removal when desired, I preferably make use of my improved locking washer 13, having the elongated or oval slot or aperture 14 and the lateral notches 15 adapted to receive a suitable spanner. In use the locking device is pressed down onto the post over the head 9 which is of shape to suitably pass 70 through the slot 14. The locking member 13 is then held and pressed downward with the spanner and given a quarter rotation, when it will lock under the projecting portions of the head, as is clearly illustrated in 75 connection with Figs. II and III, when it will prevent any possible upward movement of the barrel portion of the lever or of the actuating spring and will satisfactorily retain these parts in place. If desired, to 80 facilitate this rotative locking movement the inside of the slot 14 may have the slightly rounded portions 16 to bear against the post and keep the locking member centrally thereon, as it is termed. 90

In order to as far as possible eliminate accidental loosening or displacing of the locking member thus employed, I preferably strike the blank for the lock washer 13 to produce the spring bumps or resilient 95 portions 17 which will snap by the ends of the head as the washer is rotated, but which will project sufficiently to yieldingly engage the elongated sides of the head when the washer is in locked position and thus prevent its accidental loosening rotation although permitting of its readily being twisted loose when desired. 100

As an alternative form, in place of the oval head on the post I may simply form 105 the groove 8' and make use of the split locking washer 18 having the central recess 19, into which the body of the post will fit, and

having its lips 20 at the open or split side so rounded that they may be snapped by the post for application or removal of the locking device as desired but will ordinarily 5 exert a spring force tending to retain the locking member in position.

I claim:

1. In a device of the character described, the combination with a post having an elongated head, of a locking washer having an elongated slot to receive the head, and adapted to be secured in position by relative rotation of the post and washer, and means for resiliently securing the washer in desired relatively rotated position.
2. In a device of the character described, the combination with a bridge having a pivot seat, of a post having a threaded portion engaged in the seat and depending therebelow for engagement with a frame fastening device and having an upwardly projecting pivot portion terminating in a grooved upper end, a lever having a barrel portion rotatably mounted on the post, a spring encircling the barrel, and a resilient locking member engaged on the post above said parts for securing them in position thereon.
3. A device of the character described, including a post, a finger-piece lever and spring mounted on the post, said post hav-

ing a groove at its upper end, a locking device engaged in the groove and overlying the lever and spring to retain the parts in position, said locking device being formed from resilient material and having integral bosses adapted through the resilience of the locking device to snap into interlocking engagement with the post to secure the device against accidental disengagement.

4. In an ophthalmic mounting, the combination with a post having an elongated head, of a locking washer having an elongated slot to receive the head and adapted to be secured in position by relative rotation of the post and washer.

5. In an ophthalmic mounting, the combination with a fitting, of a post mounted on the fitting and having a portion depending therebelow for engagement with a frame fastening device and having an upwardly projecting pivot portion terminating in a grooved upper end, a lever rotatably mounted on the post and a locking member engaged in the groove of the post above the lever for securing the lever in position.

In testimony whereof I have affixed my signature, in presence of two witnesses.

WILLIAM H. BOUTELLE.
